Patented Dec. 9, 1862.

Henry S. Nuttall
Alfred S. Nuttall

Dec. 1680

Henry and Alfred S. Hubbell, of Buffalo, N. Y.
Letters Patent No: 1557. Dated Dec. 9th 1852

The schedule referred to in the Letters Patent and marking, with the same

So all whom it may concern:

We it known that we Henry S. Hubbell and Alfred S. Hubbell of the City of Buffalo, County of Erie, and State of New York, have Invented or produced a new and original design for Cooking Stoves, called the Monitor; and we do hereby declare that the following is a full and exact description of the same reference being had to the accompanying Photograph and the letters of reference marked thereon.

Figure 1 is a perspective view of the stove

Letter A Top plate. Both of the oven sides both being alike. Cone of the oven doors both being the same & the oven Top. D. D the Front of the stove E, the Front door. F the end or Fire door attached to the side of the stove M the front Bottom, or Fire Hearth of the stove.

What we claim as our Invention or production and desire to secure by Letters Patent is the general design or configuration represented in the accompanying Photograph
